UNITED STATES PATENT OFFICE.

THOMAS NATHAN RUSSELL, OF CHICAGO, ILLINOIS, ASSIGNOR TO CHICAGO-CLEVELAND CAR ROOFING COMPANY, OF CHICAGO, ILLINOIS, A CORPORATION OF ILLINOIS.

CAR END CONSTRUCTION.

1,272,116.

Specification of Letters Patent.

Patented July 9, 1918.

Application filed December 16, 1914, Serial No. 877,463. Renewed December 10, 1917; Serial No. 206,564.

To all whom it may concern:

Be it known that I, THOMAS NATHAN RUSSELL, a citizen of the United States, and a resident of Chicago, in the county of Cook and State of Illinois, have invented certain new and useful Improvements in Car End Constructions, of which the following is a specification.

My present invention relates in general to car construction and more particularly to the bodies thereof and has special reference to improvements in framing of such bodies.

The principal objects of my present invention are the provision of improved means of connecting the vertical and horizontal members constituting the frame of the car; the provision of improved means for connecting vertical metallic posts of angular cross-section to horizontal sills and horizontal metallic end plates; the provision of improved means for stiffening and strengthening a car end and generally to improve, cheapen and simplify the construction of frames for car bodies and such other objects as will hereinafter appear.

In attaining the foregoing objects and certain additional advantages to be below disclosed, I have provided the construction illustrated in the accompanying drawings, 30 in which:

Figure 1 is a perspective view of the framing of a car end constructed in accordance with my present invention;

Fig. 2 is a perspective view of a supporting shoe for the vertical posts of the car frame;

Fig. 3 is a section on the plane 3—3 of Fig. 1 illustrating the way in which the supporting shoe shown in Fig. 2 is attached 40 to the horizontal sill.

Fig. 4 is a section on the plane 4—4 of Fig. 1 illustrating more particularly the relation between the vertical post and its supporting shoe;

Fig. 5 is a plan view of the car roof shown in Fig. 1;

Fig. 6 is a perspective view of a portion of the framing of a car having wooden horizontal sills and metal vertical posts;

Fig. 7 is a plan view of the modified form of supporting shoe used in connection with wooden sills as illustrated in Fig. 6; and

Fig. 8 is a perspective view of the shoe itself apart from the sills shown in Figs. 5 and 7.

Referring now to Fig. 1, it will be seen that the framing of the car consists of horizontal channel-shaped sills 11, vertical Z-shaped posts 12, corner posts 13, and car-lines 14, and longitudinal plates 16 by which the car lines are supported. The car frame rests on two center sills 40 which are supported in turn by the bolsters of the car.

It is desirable to strengthen the ends of the car so as to prevent the ends buckling or being knocked in or out. For this purpose gusset plates 18 are attached to the side plates 16 for the purpose of connecting the latter with diagonal stays 19. These stays 19 are connected at one end to the gusset plate 18 and at the other end to the end car-lines or end plates 14. One advantage of using a gusset plate 18 as an intermediary between the side plate 16 and the diagonal stay 19 is that the strain produced by the connection between these two parts is more equally distributed along the side plate and also along the stay than would be the case if the diagonal stay was attached directly to the side plate 16. Thus not only is the side plate 16 engaged by a greater length of the gusset plate 18 than would be the case if the stay 19 was attached directly to the side plate 16, but also the length of stay engaging the gusset plate 18 is greater than would be the case without the use of such a gusset plate. To further strengthen the car end a stay 20 running parallel to the side plate 16 is arranged between the gusset plate 18 and the end carline or car plate 14.

The gusset plate 18 is preferably triangular as shown and provided with a lip 30 for engagement with the outer side of the side plate 16. This lip takes the strain off the bolts 31 used to attach the gusset plate to the beam so far as tensional strains on the stay 19 are concerned.

Further, the two stays prevent the buckling or bowing of the end outward and for this purpose the stays are preferably attached to points adjacent the center of the end carline or end plate.

With regard to the improved means adopted for connecting the vertical posts 12 and the horizontal sills 11 particular reference is made to Figs. 2, 3 and 4. In Fig. 2 is shown the shoe which supports the vertical posts 12 which is preferably made in cast iron of such shape that the vertical posts and horizontal sills are readily en-

gaged therewith and there is little strain on the bolts, rivets or the like used for connecting the members to the shoe.

The horizontal sill 11 shown in Fig. 1 is 5 channel shaped and arranged so that it presents on the inner side of the car a smooth vertical face against which the vertical face 21 of the shoe 22 rests. This face 21 serves to prevent the shoe moving outwardly under pressure from the inside of the car. In 10 the vertical direction the shoe is supported by the sill 11 not only by means of its upper face 32 on which rests the flange 23 of the shoe but preferably also by means of a bracket 24 riveted to the inner face of the sill 11 on which rests the horizontal flange 25 of the shoe. This flange or bracket 24 on the sill 11 is desirable as otherwise the inner part 26 of the shoe would have no 15 support vertically beneath it and consequently an undue strain would be placed on the shoe and on the bolt or rivets connecting the flange 23 of the sill 11.

The connection between the post 12 and 20 the shoe is shown in Fig. 4. For this purpose the shoe is formed with a Z-shaped vertical part 27, see Fig. 2, so proportioned that it will come in contact with the whole of one side of the Z-shaped post which it 25 has to support. This projecting part 27 is suitably attached to the post 12 by rivets or the like.

When wooden sills are used instead of metal sills the construction on the shoe has 30 to be modified. In the first place the wooden sills are usually wider than the iron sills so that the necessity for a supporting bracket 24 is no longer present. A depending flange 28 is provided, however, for engaging with the inner face of the sill in order 35 to prevent outward movement of the shoe thereby taking the strain off the bolts 33. The flange 28 is formed with an aperture 34 through which is passed one of the 40 bolts 35 tying together the sills 36 and 37. The projection 27^a is formed and attached to a Z-shaped post in exactly the same manner as the shoe illustrated in Figs. 2 and 4.

I claim—

50 1. In a car frame, an upper structure comprising longitudinal side plates, a transverse beam, gusset plates attached to the horizontal faces of said side plates intermediate their ends, portions depending from said 55 gusset plates attached to the vertical faces of said side plates, and diagonal members attached at one end to the gusset plate and at the other end to said transverse beam.

2. In a car frame, an upper structure comprising longitudinal side plates, a transverse beam, a triangular gusset plate attached along one side to the horizontal face of one 60 of said side plates, a portion depending from said gusset plate attached to the vertical 65 face of said side plate and a diagonal mem-

ber attached to said gusset plate along another side of said side plate, the other end of said diagonal member being attached to one of said beams.

3. In a car frame a roof structure comprising longitudinal side plates, transverse beams, gusset plates attached to one of the said side plates intermediate its ends, a diagonal member attached at one end to the gusset plate and at the other end to a transverse beam, and a member substantially parallel to the side plate beam connected at one end to the said gusset plate and at the other to the transverse beam.

4. A car frame comprising, in combination, a vertical beam, a horizontal beam, a shoe arranged on one of said beams adapted to receive the end of the beam arranged transversely thereto, a projection on said shoe adapted to engage one of each of a plurality of pairs of diametrically opposite faces of the end of the beam received by said shoe and a second projection on said shoe adapted to engage the inner side of the beam arranged transversely to said last mentioned beam.

5. A car frame comprising, in combination, a substantially vertical beam, a substantially horizontal beam of less width than said vertical beam, a shoe arranged on said horizontal beam adapted to receive the end of said vertical beam, said shoe being of greater width than said horizontal beam, a member attached to a vertical face of said horizontal beam having a substantially horizontal supporting surface below the shoe supporting surface of the beam to which it is attached, and a projection on the shoe attached to the supporting surface of said member and also to the said vertical face of the horizontal beam.

6. A car frame comprising, in combination, a substantially vertical beam of angular cross-section, a substantially horizontal beam, a shoe arranged on said horizontal beam, and a projection on said shoe projecting perpendicularly with respect to said horizontal beam and having a cross section of similar configuration to said vertical beam, and means for clamping said projection to the end of said vertical beam.

7. A car frame comprising, in combination, a substantially vertical beam of Z-shaped cross-section and a substantially horizontal beam, a shoe arranged on said horizontal beam, and a projection on said shoe of Z-shaped cross-section projecting perpendicularly with respect to said horizontal beam, and means for clamping said projection to the end of said vertical beam.

8. A car frame comprising, in combination, a substantially vertical beam, a substantially horizontal beam of less width than said vertical beam, a shoe arranged on said horizontal beam adapted to receive the end

of said vertical beam, said shoe being of greater width than said horizontal beam having a substantially horizontal supporting surface below the shoe supporting surface of the beam to which it is attached, and a projection on the shoe attached to the supporting surface of said member and also to the said vertical face of the horizontal beam.

9. A car frame comprising, in combination, a substantially vertical beam, a substantially horizontal beam, a shoe on said horizontal beam adapted to receive the end of the vertical beam, said shoe having portions adapted to contact with the horizontal

and inner vertical faces of the horizontal beam and two longitudinal faces of the vertical beam and not the faces diametrically opposite thereto, and means for clamping said faces of said beams against said portions.

In testimony whereof I have hereunto signed my name in the presence of the two subscribed witnesses.

THOMAS NATHAN RUSSELL.
